UNITED STATES PATENT OFFICE.

JOSEPH H. ADAMS, OF FLATBUSH, NEW YORK, ASSIGNOR TO THE TEXAS COMPANY,
OF HOUSTON, TEXAS, A CORPORATION OF TEXAS.

APPARATUS FOR THE CONVERSION AND TRANSFORMATION OF LIQUIDS, FLUIDS, AND OILS.

Application filed March 3, 1919. Serial No. 280,456.

To all whom it may concern:

Be it known that I, JOSEPH H. ADAMS, a citizen of the United States, residing at Flatbush, in the county of Kings and State 5 of New York, have invented a new and useful Apparatus for the Conversion and Transformation of Liquids, Fluids, and Oils, and of which the following is a specification.

10 This invention relates to an apparatus having the capacity of carrying out the oil converting process disclosed and claimed in my co-pending application Serial No. 280,455, filed March 3, 1919, and deals with 15 certain improvements in the subject matter of my other co-pending application Ser. No. 530,852 filed Dec. 1, 1909, now Patent 1,320,354, Oct. 28, 1919.

The object in view in this apparatus is 20 the construction and operation of the several co-related parts comprising the system, at a moderate cost and so constructed and designed as to enable workmen skilled in the art of oil conversion to readily operate the 25 same at a high rate of commercial efficiency especially in the transformation of high boiling petroleum and coal tar oils into lower boiling products as gasolene, naphtha, benzol, toluol and other light hydro-carbon 30 products to meet the ever increasing demand for these oily spirits and light oils.

A further object is to secure simple and inexpensive parts and features and to so arrange and co-relate the same as to render 35 available a complete organization or system capable of continuously converting hydro-carbon oils on a commercial basis. Other objects of the invention will be obvious from the annexed drawings and from the following descriptions as the combinations of elements and arrangement of parts will be exemplified in the construction hereinafter set forth and the scope of the application which 40 will be indicated in the following claims.

45 In order that this invention may be more fully disclosed and otherwise made clearly comprehensible to those skilled in the art, drawings of the many possible embodiments thereof have been appended as a part of this disclosure, and in such drawings like characters of reference denote corresponding parts throughout the several views of which:

Fig. 1, is an assembly in elevation of the

apparatus as organized for commercial operation.

Fig. 2, is a vertical sectional elevation showing one of the forms of converter which may be employed for vaporizing oil then converting the oily vapors within the same chamber.

Fig. 3, is a modified form of converter showing an expansion and separating dome above the vapor cracking chamber and which is an improvement over that shown in Fig. 2.

Fig. 4, is a cross sectional view taken through line Z—Z of Figs. 2 and 3, and shows the relative position of insulator core, electrodes and container.

Fig. 5, shows a battery of improved converters for commercial operation wherein the super-atmospheric vapor pressures are equalized through vapor and oil supply pipes, and:

Figs. 5^A, 6, 7, 8, 9 and 10 show the simple 75 construction of a form of electric heater employed for oil vaporizing and vapor cracking.

Referring now to the drawing Fig. 1, A, represents a suitable supply tank as a source 80 of the oil to be treated. Fluid oil may be admitted to this tank through pipe 1 controlled by valve 2, and the displaced air, at the time of filling, may escape through pipe 3 controlled by valve 4. This tank may be 85 provided with glass sight gauges 5, so that the height of oil therein may be known at all times.

Oil is withdrawn from the tank A, 90 through pipe 6 and sediment trap 7, by pump 8, and forced through pipe 9, precision valves 10 and pipe 11, into pre-heater B, composed of a refractory brick or asbestos and magnesia lined shell containing a heating means and a pipe coil 12, so that the 95 inflowing oil to the converter may be rapidly heated as it flows through the coils and out through pipe 13 and trap 14, into the body of the converter C—D.

This form of converter is composed of a 100 vaporizing section C, provided with a glass sight gauge 15, to record the height of oil in the section, and a thick flint glass sight 16, so that the color of the heater may be observed.

Mounted above the vaporizing section C,

and made fast thereto by interposed flange members 41, a section D, is arranged for confining the vapors of oil arising from the vaporizing section C, while undergoing the cracking operation. This section is provided with a glass sight gauge 17 and a thick flint glass sight 18, so that the color of the vapor cracking heater may be observed.

Leading out from this section D, a pipe 19, connects into the top of a gauge column 20, on which glass sight gauges 21, are arranged so as to enable the operator to more carefully observe the height of oil in the converter C—D. The bottom of this column 20, connects into the top of trap 14, so that there will be a complete circulation of oil and oily vapors through the column and gauge glasses.

Leading out from the opposite side, near the top of the section D, a vapor pipe 22, is connected into the upper part of a trap F, in which a baffle plate 23, is arranged to throw down any partially or wholly unconverted vapors before passing out through pipe 24 to the coils 25 of condenser G.

Such heavy vapors which fall in liquid condensate are led back to the section C, through pipe 26, while any lighter partially converted vapors which pass down around the bottom of the baffle plate 23, but which do not rise and flow through pipe 24 to the condenser but fall to the bottom of the trap F, flow through pipe 27 to the liquid collecting tank J, to be returned to the tank A, for re-treatment.

The vapors and gases passing through the condenser G, flow through pipe 28, into the distillate and gas collecting tank H, provided with a sight gauge glass 29 and a pressure gauge 30. From this tank the liquid oil is withdrawn through pipe 31 controlled by valve 32, and the non-condensable fixed gases are let off through pipe 33 controlled by needle valve 34.

As it is difficult to regulate the speed of a pump so as to deliver constantly a given fixed quantity of oil to the system, a pipe 35 and an enclosed pop or release valve 36, are arranged in the oil delivery system from pump 8, and by regulating the tension in the enclosed release valve 36, to a higher pressure than that maintained in the system, the pump 8, can be operated to deliver through precision valves 10, the required amount of oil to the heater and converter, and the surplus oil can be released through this valve and returned to the tank A, for re-circulation. The gauge 37, will record the pressure of oil in the delivery system while gauges 38 at the head of the converter and 30 on the running tank H, will record the back pressure in the system against which the oil must be forced by pump 8 into the converter C—D.

The lower section C, of the converter is

provided with a draw-off pipe 39 and valve 40, leading into tank J, so that this section may be emptied and cleared of any heavy oil and sediment which may have accumulated therein and the gauge 74, will indicate the height of oil in this tank.

In this form of apparatus the crown section D, is secured to the lower retort or section C, by flange members 41, which are securely bolted together against a gasket of high heat enduring material. Since the vapors rising into the crown section D, from the body of liquid oil contained in the retort section C, exert a high super-atmospheric vapor pressure, I have arranged a steel cap 42, at the top of this section and made it fast against a gasket by means of strong steel bolts.

As a means of safety in this high pressure system, should an unavoidably excessive pressure occur, a safety valve 43 is provided and arranged in the vapor line 24, above the condenser so that any sudden expansion in the system can be released without affecting the operation of the several co-related parts of the apparatus.

The liquid contents of tank J, can be returned to supply tank A, by means of a pump 45 in connection with pipe 44, provided to withdraw the oil and force it through pipe 46 into the supply tank so that with new oil it may be re-treated as before.

The heaters contained within the converting retort C—D, and which will be more fully described hereinafter, are arranged on conductor rod 47—48, to which electric current is supplied through cables +49 and —50, from a source of low voltage and high amperage, so that the maximum of heat current can be supplied at a comparatively low electro-motive force.

In Fig. 2, a vertical section of the converter shows the interior construction of the vaporizer C, and the vapor converter or chamber D. Located within this retort, the two heaters 53 and 54, are held in position by means of the conductor rod 47—47'—48, through which current flows to maintain each heater at the required temperature for their respective operations. It will be noticed that a tube or sheath 55 extends down into the vaporizing chamber C, from the flange plate 41, the object being to confine the heat from the heater and to cause the oil flowing in through pipe 13, to approach the heater 53 from below, as shown by the arrows, and to be rapidly heated and vaporized. As this sheath is in close proximity to the heater 53, some of the radiating heat therefrom will have the effect of additionally heating the incoming oil contained in the well outside the sheath so that by the time it enters the sheath and surrounds the heater it is raised almost to the point of volatilization.

The vapors rising from the surface of oil above the heater 53, enter the converting tube or section D, and come in contact with or in close proximity to the heater 54, which is maintained at higher temperature than the vaporizing heater 53. The vapor, in its upward passage through the chamber D, is affected within the heated zone and is, in a considerable measure, changed from its 10 higher boiling nature to desirable low boiling products.

These products can be separated out from the condensate by fractional distillation after the converted vapors have passed 15 through pipe 22, the condenser G and into trap tank H, from which they are withdrawn after having been reduced to liquid form.

A feature of importance in an apparatus 20 of this nature is the means for internally applying heat to the oil and oily vapors contained within the retort under high super-atmospheric pressures for the purpose of bringing about the conversion of the 25 high boiling original untreated oil to lower boiling products. In the structure illustrated electric heaters are employed for this purpose and they are adapted to be maintained at heats designed to bring about the 30 desired results and which heats must vary with the oils of different gravities and boiling points subjected to transformation by this apparatus.

Each of these electric heaters is made up 35 in the form of a grid from a plurality of resistance rods arranged in pinion like fashion and so connected that the current may flow through them to the best advantage, and while the precise manner of connecting 40 these resistance rods may be varied to adapt the heater to the available source of electricity.

This type of electric heater is especially 45 adapted for working under an electric current having a relatively low voltage or electro-motive force and a correspondingly high amperage or flow of current which is the heat generating element in the form of resistance rod I propose to employ. The current is brought in by means 50 of cable or conductor wire +49 and conductor rod 47, which passes through the cap 42 at the top of chamber D, and in order to prevent grounding or short circuit 55 with the metallic parts of the system, an insulator bushing 51, of suitable non-conducting material will be interposed in a tight fitting relation between the cap and a stuffing box or gland 52, provided for the 60 leading in conductor rod 47, so that vapor leakage under high pressure may be avoided.

So also the leading out end of the conductor rod 48, through the bottom of the chamber C, may be provided with an insulator bushing and a gland. The conduc-

tor rod 47-48 is divided into three parts, that above the heater 54, and extending out through cap 42, that part connecting heater 54 with 53, and that part extending below heater 53 and out through the bottom of 70 chamber C. The upper and lower parts of this conductor terminate within the retort C-D, in electrical connection with corresponding terminals of suitably constructed heaters 53 and 54, which comprise one 75 or more resistance rods 60, 60^a, 60^b, 60^c, etc., (Fig. 5^a).

These heaters provide means for internally heating the oil and oily vapors so as to very effectually convert the same and assist in performing the steps of primary importance to my process, that is the vaporizing of oil, then transforming the vapors therefrom in the same receptacle.

In Fig. 3, a similar sectional view of a 85 retort is shown comprising in addition an expansion dome E. This dome is made fast to the chamber D, by means of a reducing flange 56, and at the upper end of the dome a crowned cap 57, is provided for the attachment of the cap 42, through which the upper part of the conductor rod 48 extends. 90

Within this dome E, one or more arched 95 perforated baffle plates 58, may be arranged to intercept the vapors before they escape through pipe 22 to the condenser G. The central part of these plates is cut out so as to permit the rod 47-48 supporting the heaters 53 and 54 being removed from the top of the dome when required.

The pieces 59, cut from the central part of the plates 58, are attached to the rod 47-48, in such a position as to close the opening in the large plates 58, when the rod is properly located, but in the drawing these small plates are shown mounted above the larger ones for illustration purposes only as, in practice, they are so positioned as to form one continuous arched plate for the interception of the heavier vapors.

The object of these plates is to collect any partly or wholly unconverted oily vapor and cause it to flow down along the inside of the dome E and reducing flange 56, where it will come into close proximity to the cracking zone or continue down the sides of chamber D, and fall into the chamber C, where it will again be volatilized by heater 53, and eventually become changed when in vaporous form by the heater 54.

In Fig. 4, the relative position of the heater rods 60, insulating core 69, sheath 55 and the wall of the chamber C, are shown as well as the inlet pipe 13 and one of the outlet pipes 39.

In the erection and operation of the converters, for commercial practice, it may be necessary to combine a number of units into a battery so that the supply and discharge to and from them can be handled by 130

one set of supply pumps and the converted vapors by one condensing apparatus, for economy of operation. Such a battery of units is shown in Fig. 5, where three of the 5 converters of the type shown in Fig. 3, are combined with a uniform feed and discharge.

The number of units may be increased as desired for convenience and economy, and 10 each supply is compensated with the supply to the other converters, by such a pipe as 68, so that a uniform height of oil may be maintained in all of the vaporizing chambers C¹, C², C³, and any additional 15 ones comprising the battery. In like manner the outlets 22, from the domes E¹, E², E³, lead up through pipes 70 and down through pipes 71, into one inclined vapor pipe 24, leading to the condenser G, from 20 which they pass into collecting tank H, as described in connection with the apparatus shown in Fig. 1.

I am not herein claiming this liquid or vapor compensation method, however, as 25 that has already been shown and described in my co-pending application Ser. No. 530,852, filed Dec. 1, 1909, now Patent 1,320,354, Oct. 28, 1919, nor am I claiming the form of heater shown in this application 30 for that appears in my Patent 976,975, Nov. 29, 1910, and is fully described in my co-pending application 530,852 already referred to, but I do claim the combination 35 with an oil vaporizer of an oily vapor heater and for the avoidance of cross reference I will again describe this simple form of heater so that the description may be embodied in this specification.

It is, of course, a well known fact that if 40 certain resistance mediums are employed through which an electric current will pass, heat will be generated, and if the material is of a nature to constantly withstand high temperature without breaking down or dis- 45 integrating then a constancy of heat can be depended upon for commercial operation. Such material can be found in a form of graphitic-carbon made in the electric furnace and this material can easily be cut, 50 threaded, tapped and shaped into the forms required for this purpose.

The most convenient form for the resistance elements will be the round pencils of various thicknesses and lengths threaded 55 at both ends so that attachments can be made as shown in the drawing Fig. 5^a. In this form of grid the rods are joined at the top by links as 63 and 65, having nuts of the graphitic-carbon located at both sides of 60 them, while at the bottom the rods are screwed into links as 62 and 64, tapped to receive the screw threaded ends of the rods.

In order to intercept the current passing 65 in through rod 47 at the top of the unit and cause it to flow through the grid, a

core 69, of soapstone, porcelain or other insulating material capable of withstanding temperatures above 1000° F., is provided with metal ends 72, as shown in Fig. 6, and the grid of heating elements is wrapped 70 around this core having the link end 61, at the top, made fast to the part 72 by means of nut 73, and at the bottom the link 67, is made fast in a similar manner to a corresponding metal part. In this manner the 75 current coming down through rod 47, passes through metal end 72, the link 61, down the rod 60, across the link 62, up the rod 60^a, across the link 63, down the rod 60^b, across the link 64, up the rod 60^c, across 80 the link 65 and continues up and down the successive rods and out at the last rod 66 and link 67 to the lower metal part attached to the insulating core 69, and so on to the next heater.

The complete heater composed of the core and grid with the metal ends 72 the core 69 and the resistance elements 60, is shown at Fig. 7, and in Fig. 8, a top view of the heater is shown while in Fig. 9, a cross section through line X—X of Fig. 7, shows the relative position of the core 69 and resistance elements 60. Fig. 10, is a view looking down below the line X—X of Fig. 7, and shows the lower link 67, in a position 95 one rod removed from that to which link 61 is attached at the top of the heater.

This form of grid heater can have one or more circles of resistance rods and in commercial practice a greater volume of 100 heat is radiated from several circles of smaller diameter resistance rods than from a single circle of larger diameter resistance rods.

Mode of operation.

105

Having described one form of apparatus adapted to carry out my process referred to, it will be apparent to those having any knowledge of the art that while working 110 under high super-atmospheric vapor pressures as contemplated, there are several things which must be observed in order to obtain the objects sought and to get, as a result of employing this apparatus, the desired low boiling products of the highest 115 commercial value and nature.

It will be understood from the foregoing description that original oil is contained in tank A, that pump 8, withdraws oil from the supply tank and delivers it against a back vapor pressure into the converting and condensing system composed of parts B, C—D—E, F, G and H, and that the surplus oil not forced into the converter is delivered 120 into the tank A, through pipe 35 and enclosed release valve 36, for re-circulation by the pump 8. That the oil so admitted into the system through precision valves 10, is pre-heated in the heater B, then admitted 125 130

into the vaporizer C, where heat from the electric heater 53, volatilizes the oil, and that such vapors arising from the surface of oil in this container pass up through chamber D, and in close proximity to the heater 54, where the greater part of such vapors are affected by the cracking heat radiated from the electrodes and while held under the high super-atmospheric vapor pressures 10 are transformed from high-boiling oils into products having lower boiling points and specific gravities.

The vapors so transformed pass out through pipe 22, trap F and into the condenser and collecting system G and H, from which latter the liquid product is withdrawn through pipe 31 controlled by valve 32 and the fixed gases through pipe 33 controlled by valve 34. Any condensate not 20 light enough to go over into the condenser, when in vaporous form, is returned to the chamber C, or trapped in tank J, from which it is returned to the supply tank A, by means of pump 45 and pipes 44 and 46.

25 In this process, as carried on in this apparatus, the addition of new oil into tank A, is necessary to compensate for the withdrawal of distillates from the running tank H, and so long as the apparatus is operating 30 under favorable conditions with the heaters maintained at uniform heats and the supply and discharge regulated to render the greatest volume of transformed product the apparatus may continue in operation for days 35 without cessation or disturbance.

While this apparatus has a wide range in its adaptability for various purposes and for the treatment of other liquids than hydro-carbons, its mission in this case is to 40 fulfill the need for a method of transforming many of the heavy and inexpensive residues of the petroleum and coal tar group into those of greater commercial demand and value to meet the fast growing market 45 necessities, particularly for petroleum spirits such as gasoline and naphtha.

The terms "cracking heat" and "cracking temperatures" may be understood and interpreted as temperatures in excess of the 50 necessary heats employed for the fractional distillation of oils or the mere separation of the component parts of a crude or semi-refined oil. Cracking temperatures as applied to petroleum oils may vary from 600 to 1000° F., or even higher, but for commercial purposes in the handling of ordinary residues and the lower gravity oils available 55 for conversion I have found that heats ranging from 700 to 900° F., and vapor pressures of 70 to 90 pounds to the square inch over the surface of oils and in the vapors undergoing transformation and condensation give very satisfactory results without, however, using these illustrations in a 60 limited sense.

An apparatus of preferred form and construction has been illustrated and described for the purpose of showing a way in which this invention may be used, but the inventive thought upon which this application is 70 based, is broader than this illustrative embodiment thereof, and I therefore intend no limitations other than those imposed by the appended claims:

Claims—

1. Apparatus of the nature disclosed, comprising a receptacle, an electric oil heater arranged in the lower part of said receptacle, an electric vapor heater arranged in the upper part of said receptacle, means rigidly connecting said heaters with said receptacle whereby a fixed normal relation may be maintained between the same and means for supplying oil to said receptacle and maintaining it at a pre-determined level above 80 said oil heater in the lower part of said receptacle.

2. Apparatus of the nature disclosed, comprising a receptacle an electric oil heater in the lower part and an electric oily vapor heater in the upper part arranged within said receptacle and a heat confining partition, having an oil inlet opening, interposed between said lower heater and the adjacent 90 wall of said receptacle for the purpose of confining heat from the lower heater to a small localized portion of oil contained within the lower part of said receptacle to be volatilized.

3. Apparatus of the nature disclosed, comprising a receptacle, electric heaters arranged in the lower and upper parts of said receptacle comprising aligned electrical conductors, interposed insulating members, circumferentially arranged resistance rods surrounding said insulating members, links connecting the adjacent ends of said rods, means establishing electrical connections between said rods and conductors, means for raising temperatures of oil to volatilization in the lower heater, means for raising temperatures for vapor cracking in the upper heater, means supplying oil under high pressure to the lower part of said receptacle and means withdrawing converted vapors from the upper part of said receptacle cooling and condensing them under high super-atmospheric vapor pressures.

4. Apparatus of the nature disclosed, comprising means for intimately subjecting oil to vaporizing temperatures while contained within an enclosed receptacle for causing copious volatilization, means for affecting the vapors of volatilized oils by electrically maintained heaters enveloped within the oily vapors while contained in the same receptacle, means for forcing oil against a back high vapor pressure into the lower part of said receptacle, means for withdrawing converted and transformed oily vapors from the 120 125 130

- upper part of said receptacle, means confining a small body of liquid in the immediate proximity of the liquid heater. 65
5. Apparatus of the nature described, comprising a plurality of oil converters containing oil vaporizing heaters and heaters for converting the vapors of volatilized oils while held under high super-atmospheric vapor pressures, means for supplying oil to the converters and maintaining a substantially uniform level therein, means for separating from the vapors generated the partially or wholly unconverted oils and for returning and re-treating that oil, means for withdrawing and condensing the converted vapors from the said converters and means for maintaining said pressures on said oil and in said vapors in the converters to and through the condensing means. 70
10. Apparatus of the nature described, comprising a combined vaporizing and cracking chamber, means for supplying oil thereto and maintaining a predetermined level therein, means for heating the body of oil in the chamber to effect its vaporization, means for applying a cracking temperature locally to the evolved vapors above said body of oil in said chamber, means for maintaining superatmospheric pressure within said chamber, means for separating out the heavier and medium products from the lighter products, means for returning the heavier products to the body of liquid in the chamber and the medium products to the source of supply, and means for condensing the lighter products of desired volatility. 80
15. Apparatus of the nature disclosed, comprising a source of oil, a receptacle connected therewith, and heaters combined with said receptacle adapted to be maintained at oil volatilizing and oily vapor cracking temperatures in contact with the oil and oily vapors therein, an outlet for the oily vapors evolved by the action of said heaters, a receptacle connected with said outlet and adapted to collect portions 85
20. of the oily liquid carried by said vapors, means for returning said collected liquid to the action of said heaters, means for condensing the residual vapors, and means for maintaining the entire system under high 90
25. super-atmospheric vapor pressure from the source of supply through to the end of or beyond the condenser. 95
11. Apparatus of the nature described, comprising a plurality of combined vaporizing and cracking chambers containing oil vaporizing heaters and heaters for converting vapors of volatilized oils, means including interconnecting pipes between the chambers for supplying oil to the several chambers and maintaining a substantially uniform level therein, means for maintaining superatmospheric pressure in the vapor spaces of said chambers, means for withdrawing the evolved vapors, and means for separating out and returning for retreatment certain heavier constituents of the withdrawn vapors. 100
30. 12. Apparatus of the nature described, comprising a plurality of series connected combined vaporizing and cracking chambers, means for passing oil continuously through said chambers in succession, means for heating the oil in transit through said chambers to effect its vaporization, means disposed in the vapor spaces of the several chambers for locally subjecting the evolved vapors to sufficient heat to effect their conversion, means for maintaining superatmospheric pressure in said chambers and means for withdrawing the evolved cracked products therefrom. 110
35. 13. Apparatus of the nature described, comprising a plurality of series connected combined vaporizing and cracking chambers, means for passing oil continuously through said chambers in succession, means 115
40. 45. 50. 55. 60. 65. 70. 75. 80. 85. 90. 95. 100. 105. 110. 115. 120. 125.
7. Apparatus of the nature disclosed, comprising a receptacle, an electric oil heater in the lower part, and an electric oily vapor heater in the upper part arranged within said receptacle and a heat confining partition, having an oil inlet opening, interposed between said lower heater and the adjacent wall of said receptacle for the purpose of confining heat from the lower heater to a small localized portion of oil contained within the lower part of said receptacle to be volatilized and means for regulating the flow of oil into the lower part of said receptacle and the withdrawal of vapors from the upper part thereof. 110
8. Oil converting apparatus comprising a converter having a liquid section therein, means for maintaining body of liquid oil therein a heater within said body of oil, a heater within the vaporizing space for cracking the vapors evolved by the heater in the liquid, and means for partially con-

for heating oil in transit through said chambers to effect its vaporization, means disposed in the vapor spaces of the several chambers for locally subjecting the evolved vapors to sufficient heat to effect their conversion, means for maintaining superatmospheric pressure in said chambers, means for withdrawing the evolved cracked products therefrom and means for freely connecting

the vapor spaces of the several chambers to 10 equalize the vapor pressure therein.

In testimony whereof I affix my signature in the presence of two witnesses.

JOSEPH H. ADAMS.
